UNITED STATES PATENT OFFICE.

JOHN J. PARKER, OF BRIDGEPORT, CONNECTICUT.

WINDOW-OPERATING DEVICE.

Application filed January 6, 1921. Serial No. 435,550.

To all whom it may concern:

Be it known that I, JOHN J. PARKER, a citizen of the United States, and resident of Bridgeport, in the county of Fairfield and State of Connecticut, have invented certain new and useful Improvements in Window-Operating Devices, of which the following is a specification.

This invention relates to improvements in power devices for window sash operators and is more especially useful when employed for manipulating a series of sash arranged side by side in alignment and connected to be operated simultaneously.

An object of the invention is to provide a simply and practically constructed device of the present character having mechanism through which the power is designed to be greatly multiplied.

A further object is to provide a power device including a novelly constructed housing having an oil receiving pocket whereby provision may be made for continuous lubrication of the worm and segment carried by the manipulating shaft of the power device and the operating shaft of the sash operator, respectively, and adapted to mesh with each other when the sash are being moved to or toward open or closed position.

Still further objects are to provide in a device of the type mentioned a novelly constructed segment adapted to be rigidly located upon operating shafts of varying diameters without the necessity of milling or fitting the segment upon the operating shaft, and to provide an improved chain guide capable of being swivelly arranged upon the manipulating shaft of the power device in position to ideally perform the function for which it is intended.

With the above and other objects in view, the invention resides and consists in the construction, arrangement and combination of parts as now to be fully described and hereinafter specifically claimed, it being understood that such changes in details of construction and arrangement of parts may be made as fall within the spirit of the invention and within the scope of the appended claim.

In the accompanying drawing forming a part of this specification, wherein like numerals represent corresponding parts:

Fig. 1 is a front elevation of the power device;

Fig. 2 is a vertical sectional view on line 2-2 in Fig. 1;

Fig. 3 is a sectional plan view, on a reduced scale, of a series of windows provided with sash operators and with a power device made in accordance with the principles of the invention as disclosed in Figs. 1 and 2; and

Fig. 4 is a vertical sectional view of a modified form of the invention.

In Fig. 3 of the drawing, 5 represents a window casing and 6 a window sash pivotally hung in the openings thereof. The window sash operating mechanism therein shown is of a well known commercial type, and includes an operating shaft 7 to which are rigidly secured, as indicated at 8, any desired number of arms 9 pivotally attached, as shown at 10, to preferably longer arms 11 having their opposite ends pivoted upon the window sash as indicated at 12. The operating shaft may be mounted adjacent to the window in any desired manner as by means of bearing brackets 13 carried by the window casing and, it will be at once apparent, when the operating shaft is rotated in its bearings, it will cause the sash to swing on their pivots or hinges, either toward or from the window casing; that is to say, arms 9 will cause arms 11 to move toward or from the casing.

The novel power device now to be described and adapted to be manually actuated is for the purpose of rotating the operating shaft in either direction.

Referring more especially to Figs. 1, 2 and 3, 14 denotes a pair of L-shaped brackets attached to the window casing in spaced relation with respect to each other. Adjustably secured to these L-shaped brackets, as indicated at 15, are attaching flanges 16 of a housing 17 of peculiar construction. This housing has side walls 18 and top and bottom walls 19 which are, respectively, 100 preferably parallel with each other, and an end wall of any desired configuration but preferably of about the shape shown and consisting of a curved portion 20 and a flat portion 21. The portion of the housing 105 lying closest to the window casing is open, except that there is a flange 22, preferably parallel with flat portion 21, that extends from side to side of the housing and upwardly from the bottom wall thereof to provide an oil receiving pocket 23 for a purpose to be explained. In the upper por-

tions of the side walls of the housing are arranged bearings adapted to receive operating shaft 7 of the sash operator in the manner shown, and arranged upon the shaft 5 and within the housing is a segment 25 having teeth 26 adapted to engage a worm 27 also within the housing and preferably integral with a manipulating shaft 28 mounted in bearings 29 in flat portion 21 and flange 10 22 and having a preferably square portion 30 adapted to receive a wheel 31 having an opening of similar shape. The outer end 32 of the manipulating shaft is threaded, and a nut 33 is for the purpose of holding the 15 wheel upon the squared portion of the shaft. Segment 25 is preferably constructed in the manner shown; that is, the segment is a split one, it being provided with a slit 34 extending from its opening to its circumference. Adjusting screw 35 serves the purpose of adjusting the size of the opening of the segment, as will be obvious, and set screw 36 is for the purpose of making the segment rigid upon the operating shaft. 20 Nut 37 upon the inner end of shaft 28 insures the position of the shaft in its bearings, and a chain 38 may be utilized to rotate the wheel.

The manipulating shaft is provided with 30 a reduced cylindrical portion 39 arranged between the squared portion and the bearing in flat portion 21 of the housing, and swivelly arranged upon this cylindrical portion is a hub 40 from which a pair of diverging arms 41 extend downwardly. The lower end of each of arms 41 is offset to provide horizontally arranged guide members 42 having guide openings 43 therein through which the chain is adapted to 40 freely pass, and the guide members are spaced at proper distance from each other to prevent the chain from running off the wheel.

The method of operating the device is apparent. When the chain is manipulated to turn the wheel in either direction, the worm will mesh with the segment to turn the operating shaft of the sash operator. By supplying the pocket of the housing with 50 a small quantity of oil, the worm, and consequently, the segment with which it meshes, will at all times be lubricated. By swivelly supporting the chain guide upon the manipulating shaft, the guide members will at 55 all times assume their proper relation to the manipulating wheel.

In Fig. 4 I have disclosed a modified form of the invention in which manipulating shaft

28' is disposed vertically and extends downwardly and wheel 31' fixed thereon may be 60 positioned close to the floor to be manually turned without the use of a manipulating chain. The housing 17' may be similar to housing 17. It need, however, have but one attaching flange 16' adapted to be supported 65 by L-shaped bracket 14', and it is arranged so that its wall consisting of curved portion 20' and flat portion 21' is longitudinally disposed, as very clearly shown. The operating shaft of the sash operator may have 70 bearings in side walls 18' in precisely the same manner as in the case of the device of the preferred form, and the segment 25' may be similarly constructed. An L-shaped bracket 44 secured to the casing or other 75 support rotatably receives manipulating shaft 28' to which the wheel is rigidly secured in any desired manner, as by means of a set screw 45. The manipulating shaft is mounted in bearings 29' in flat portion 80 21' and flange 22', as in the case of the device of Figs. 1, 2 and 3, and the manipulating shaft is supported from the window casing by means of a suitable collar 46 carried by bracket 44. The wall consisting of 85 curved portion 20' and flat portion 21' in the present instance constitutes the bottom of an oil receiving pocket 23'. The device of the modified form operates exactly as does the preferred device, except that wheel 90 31' is rotated without the use of a chain.

What I desire to claim is:

A power device for window sash operators, comprising a one-piece housing consisting of side walls, and a continuous integral connecting wall having one end terminating in spaced relation to an opposed portion thereof to provide an opening to the interior of the housing, said side walls and connecting wall defining an oil containing reservoir, a manipulating worm shaft journaled in the housing, means for rotating said shaft, a sash operating shaft journaled in said housing, a segment gear mounted on said operating shaft and meshing with said worm, and a set screw engaged through the untoothed portion of said segment with the shaft and accessible through said opening of the housing.

Signed at Bridgeport in the county of 110 Fairfield and State of Connecticut this 4th day of January A. D., 1921.

JOHN J. PARKER.
